UNITED STATES PATENT OFFICE.

EDGAR ALFRED WRIGHT, OF FORT MADISON, IOWA.

IMPROVEMENT IN PLOW-CLEVISES.

Specification forming part of Letters Patent No. 128,087, dated June 18, 1872.

To all whom it may concern:

I, EDGAR ALFRED WRIGHT, of Fort Madison, Iowa, have made a new and useful Improvement in "Plow-Clevises," of which the following is a specification:

My invention relates to clevises; and consists in the novel construction of a clevis with a series of perforated and projecting flanges, and adapting thereto an auxiliary clevis, the whole being so arranged as to hold the whiffle-tree firmly in a horizontal position upon a draw-bar while allowing full play horizontally, as hereinafter described.

A of the drawing represents my main clevis, which is constructed in the usual manner, except that I add to the front end thereof a series of perforated and projecting ears or flanges, marked B. The letter C represents an auxiliary clevis having flanges or ears, marked D, upon its rear end, adapted to fit closely within the ears B of the main clevis, and to be held in position by a bolt, nut, and screw, in the manner shown in Fig. 1.

The main jaws of this auxiliary clevis are adapted to receive and hold the whiffle-tree. The whiffle-tree has an opening through its front side and at its longitudinal center, and when in position an ordinary draft-bolt is passed through said main jaws and through the whiffle-tree, thereby holding it securely and firmly between said jaws on a line parallel with the draw-bar or plow-beam, and at the same time allowing fair play therefor horizontally.

Having thus described my invention, what I claim as new, and desire to secure by Letters Patent, is—

The improved clevis herein described, constructed with the main clevis A having flange B, and the auxiliary clevis C having flanges D, substantially as and for the purpose specified.

EDGAR ALFRED WRIGHT.
